UNITED STATES PATENT OFFICE.

THEODOR LÜKE, OF ST. LOUIS, MISSOURI.

IMPROVED CARPET-CLEANING MACHINE.

Specification forming part of Letters Patent No. **88,188**, dated March 23, 1869.

To all whom it may concern:

Be it known that I, THEODOR LÜKE, of St. Louis, in the county of St. Louis and State of Missouri, have made certain new and useful Improvements in Carpet-Cleaning Machines; and I do hereby declare that the following is a full and clear description thereof, reference being had to the accompanying drawings, and to the letters of reference marked thereon.

This invention relates to machines for cleaning and dusting carpets, mattings, and floor or other cloths; and the nature of the said invention is, first, in the adaptation of a suitable apron of hooks and ropes for attaching the carpets to the winding drums or rollers, so that all parts of the carpet may reach the surface of beater-action; and, secondly, in the method of attaching the lashing ropes or strips to the revolving beater-arms, as will more fully hereinafter appear.

To enable those herein skilled to make and use my said improvement, I will now describe its detail construction and operation, referring to—

Figure 1 as a plan; to Fig. 2 as an end elevation; to Fig. 3 as a sectional elevation; and to Fig. 4 as a detail view of the attachment of the lash to the beater-arm.

The general arrangement of my said machine is similar to that described in the Letters Patent issued to me for improved carpet-cleaner, numbered 65,683, and dated June 11, 1867.

The operating devices of this improvement are supported in a proper wooden frame, A. The drum B receives the carpet or matting, this being wound up thereon.

In the operative condition of the machine, the carpet passes up and over the roller C, and around the roller D at the rear end of the frame A, and therefrom to the drum E, whereon it is wound. As the carpet is unwound from B it is cleansed by the beaters and lashes; and in order that the ends of the carpet may be reached by the beaters I arrange the ropes F and hooks f, said ropes attaching to the drums whereon the carpet is wound, and holding the carpet by said hooks f, as indicated in Fig. 3.

In order that the carpet shall be caused to traverse, I arrange to rotate the drums B and

E as follows: From the pulley H, which is driven by the power-source, I connect by belt h with the intermediate pulley I. On the same shaft with said pulley I is the smaller pulley i, with belt K, connecting with the pulley k on the shaft e of the drum E, and driving said drum. A smaller pulley, k', on the same shaft and the belt L transmit motion to the pulley l on the shaft b of the drum B, thus rotating the same.

In order to cleanse the carpet in its traverse, as aforesaid, I arrange the beater-shaft M, driving the same by belt M¹ and pulley M², connecting with the power-shaft. On said shaft M are arranged the arms m, which hold the lashes m¹. As the shaft M is revolved, the lashes m¹ strike the carpet while traversing between the roller C and the drum B, and thus cause the dust to fly off.

As it frequently occurs that the carpet is not of the full width, and that some of the beater-lashes would thus lash the sub-frame, and not the carpet, I have arranged the lashes m¹ for ready removal or reattachment, as follows: To the forward end of the arms m I secure the hooks m², as in Fig. 4, these hooks being closed by the spring m³. To the end of the lashes m¹ I connect a suitable ring, m⁴, and said ring being slipped into the hook (by depressing the spring for the passage) the spring m³ then prevents the ring m⁴ and the lash from disengagement from the hook m².

In the operation of my machine, when the lash would be liable to touch the sub-frame, or be otherwise non-active, the operator may readily remove the lash and its ring from the hook m³, and, similarly, when an additional lash is needed, such may be readily inserted on the arm m, as required, and this without interruption of the operation of the machine.

To more thoroughly cleanse the carpet a rotary brush, N, is arranged to operate upon the carpet as it traverses between the rollers C and D.

When the carpet is subject to the action of the lashes m¹, in order that these may not tear through or otherwise injure the same, I arrange between the roller C and drum B an inclined frame, P, with the spring-battens O for an elastic support to the carpet. Said battens are loosely guided in the end strip O', and are supported on coiled or other spring o, thus permitting

the carpet to deflect under each lashing. In order that the deflections shall not be excessive, the frame P is arranged to limit the descent of the battens O; and to limit the rebound of the batten under impulse of the spring o, a check-wire, o', is attached to the frame P, the end being therein secured, and the upper end of said wire o' being fastened in the batten O thus limiting the rebound aforesaid by the length of said check-wire, as indicated in Fig. 3.

It is plain that by the rebound of the battens O, the cleansing operation is greatly increased, and that by the especial construction of the parts as here detailed no damage can be done to the carpet or other cloth in said operation of cleansing.

Having thus fully described my invention, what I claim, is—

1. In combination with the rollers of a carpet-beating machine, the apron attachment composed of the hooks and ropes, substantially as hereinbefore described.

2. Also making the flexible beaters removable by means of snap-hooks, or equivalent devices, substantially as set forth.

In witness of said invention I have hereunto set my hand in the presence of—

THEODOR LÜKE.
